AMMUNITION

Robert T. Catlin, Stratford, Conn., assignor to
 Remington Arms Company, Inc., Bridgeport,
 Conn., a corporation of Delaware

Application February 22, 1945, Serial No. 579,215

10 Claims. (CL. 102—56)

1 This invention relates to projectiles, and, in particular, to an improved device for arming projectiles of the explosive and pyrotechnic type.

The projectile shown and described is a .60 caliber bullet, but it will be understood that this is by way of illustration only and that the invention is comprehensive of other embodiments and includes all modifications within the scope of the appended claims.

In general, projectiles of the type hereinafter described comprise an explosive or pyrotechnic charge which is adapted to be ignited by a primer or similar type of percussion sensitive means which, in turn, is ignited by the sharp blow of a firing pin. The latter is usually carried in the nose of the projectile. When the pin projects from the nose of the projectile, the latter is said to be armed, and, on hitting a target, the pin is driven rearwardly striking the primer and igniting the explosive charge. Normally, the end of the firing pin is held within the nose of the projectile so as to render the projectile safe and is made to project automatically from the nose to arm the projectile as it moves down the barrel of the gun.

The primary safety requirements of this and similar types of projectiles is that they shall not explode inadvertently while in the barrel of the gun. This has occurred heretofore with previously known projectiles of this type due to the possibility that, if dropped on its nose or otherwise dented so as to obstruct the firing pin aperture, the pin is prevented from moving forward out of the nose of the projectile to its armed position. Consequently, the automatic function of arming the projectile as it moves through the barrel causes the primer to be indented and the projectile to explode.

An object of the invention is the provision of an improved explosive projectile which is adapted to be armed automatically when fired from a gun, but will not explode inadvertently in a gun barrel. A further object is to provide improved arming means for explosive and pyrotechnic type projectiles. A still further object is to provide arming means for explosive and pyrotechnic type projectiles having improved means for insuring safe and dependable operation thereof.

These and other objects, features and advantages of the invention will be described in detail in the specification, reference being made to the drawing in which:

Fig. 1 is a side elevation, partly in section, of

2 a projectile embodying the improved arming means of this invention, the elements of the projectile being in their normal position of assembly.

Fig. 2 is similar to Fig. 1, but shows the related positions taken by the elements of the projectile in arming the projectile as it travels through a gun barrel.

Fig. 3 shows the armed projectile of Fig. 2 at the moment of impact with a target.

Fig. 4 shows how the projectile of Fig. 1 is rendered safe after having been accidentally dropped on its nose so that an obstruction is formed in the firing pin aperture.

Referring to the drawing, Fig. 1 shows a projectile comprising a hollow body 10 having an ogive or nose 11 provided with an axial aperture 12. The latter is reduced in diameter adjacent the tip end of the nose to provide an annular shoulder 13. The rear or heel portion 14 of the body 10 is of reduced diameter and its end is provided with an inwardly sloping annular bevel 15. A cup-shaped member 16 having a flat base 16' and consisting of a relatively soft deformable material, such as gilding metal, is adapted to make a tight fit over the reduced heel portion 14 of the body 10. This cup-shaped member has the dual functions of a sabot and a heel closure, and, for brevity, will hereinafter be referred to as a sabot cup. It will be noted that the outside diameter of the sabot cup is slightly greater than that of the body 10 as a consequence of which the cup will take the rifling of a gun barrel in the manner characteristic of sabots.

Mounted in the longitudinal bore 17 of the body 10 is a core piece comprising an elongated substantially cylindrical cup-shaped member 18, the base 18' of which is adapted to abut the base 16' of the sabot cup. The core piece is somewhat shorter than the bore 17 of the body 10 so that when assembled therein a space 180 will be provided normally in the projectile between the forward end of the core piece 18 and the forward end or wall 17' of the bore 17. The core piece is dimensioned so as to make a smooth sliding fit in the bore 17 and is adapted to move forwardly into the space 180 as hereinafter described. The core piece 18 is filled with an explosive or pyrotechnic material 19 and is closed at its forward end by a suitable percussion sensitive igniter indicated generally at 20. In the present embodiment, the igniter 20 comprises a standard battery cup, the outside diameter of which corresponds substantially to the inside

diameter of the core piece 18 so that the battery cup makes a relatively snug fit therein. As shown, the forward edge of the battery cup is provided with a flange 20' by which the cup is supported in the end of the core piece and is positively held from rearward movement therein when struck by the rearwardly displaced firing pin.

The firing pin is designated by the numeral 22 and comprises a cylindrical pin dimensioned to have a smooth fit in the aperture 12 of the nose 11. The rear end of the pin is split or slotted as at 23 to form a bifurcation or fork and normally, that is to say when in assembled position, the rear extremity of each leg 24 of the fork extends into the space 180 and is bent outwardly slightly as at 24' so as to frictionally engage the edge of the aperture 12 in the wall 17' and hold the firing pin 22 in retracted position in the nose 11. The forward end 25 of the firing pin is of reduced diameter to provide an annular substantially square shoulder 26 adapted to positively engage the annular shoulder 13 of the aperture 12 to prevent the firing pin 22 from being driven all the way out of the nose. In its normal retracted position, the front end 25 of the pin is substantially flush with the end of the nose 11, the shoulder 26 of the pin being spaced rearwardly of the shoulder 13. In its forward or projectile arming position, see Fig. 2, the rear extremities 24 of the pin are squeezed together as hereinafter described and are moved forwardly into the nose aperture 12 so that the forward end 25 of the pin projects beyond the nose of the projectile. In the armed position, the shoulder 26 of the pin may be in contact with or in close proximity to the shoulder 13 of the aperture.

Mounted in the space 180 and transversely of the bore 17 is a relatively thin apertured metal washer 27 substantially equal in diameter to the diameter of the bore 17, its aperture 27' being slightly larger than the diameter of the firing pin 22. The washer is adapted to be positively held against the cap 200 of the battery cup 20 by the spread extremities 24' of the firing pin when the latter is in its normal position, as shown in Fig. 1, the spread of the extremities 24' being only sufficient to enable the latter to engage the washer at diametrically opposite points at the edge of the aperture 27'. The washer 27 has a relative free fit in the bore 17 so as to be capable of forward movement in the space 180 in the manner and for the purpose described below.

Fig. 2 shows the elements of the projectile in their new and related positions immediately after the projectile begins to travel down the barrel of a firearm. The pressure of the gas acting against the sabot cup 16 has indented the base 16' of the cup, this effect being facilitated by the annular bevel 15 on the end of the body 10; and in so doing, the core piece 18, together with the battery cup 20 and washer 27, has been thrust forwardly in the bore 17 of the projectile closing the space 180 at the forward end thereof. The forward thrust of the metal washer 27 against the spaced extremities 24' of the firing pin has forced the extremities against the edge of the firing pin aperture 12 in the wall 17' so that the extremities have been cammed or squeezed together enabling the firing pin to move forwardly in the aperture 12. When the core piece 18 has reached its foremost position in the bore 17, the washer 27 is substantially flat against the wall 17' and the forward end 25 of the firing pin ex-

tends beyond the nose of the projectile. The projectile is thus automatically armed.

Fig. 3 shows the new and related positions of the elements of an armed projectile at the instant of impact with a target T. The firing pin 22 has been driven rearwardly in the aperture 12 of the nose 11, and, inasmuch as the rear extremities 24' of the firing pin have been previously squeezed together, these elements are able to pass freely through the aperture 27' of the washer and to strike a sharp blow on the cap 200 of the battery cup 20 thereby igniting the explosive charge 19 in the core piece.

As pointed out above, a condition might arise wherein the aperture 12 in the nose of the projectile is accidentally obstructed or provides an obstruction against the relatively free forward movement of the firing pin at the time the percussion sensitive device is moved up against the rear end of the pin. Heretofore such conditions have caused the projectile to explode in the barrel of the firearm. The projectile of this invention precludes such hazardous potentialities.

Thus, assuming that the projectile has been accidentally dropped on its nose and that as a result the end of the nose has been dented forming an obstruction at the end of the aperture 12 which effectively prevents the firing pin from being moved forwardly out of the nose, as shown in Fig. 4; then, when the base 16' of the sabot cup is indented by gas pressure developed in the barrel and the core piece moves forwardly forcing the washer 27 against the rear extremities 24' of the firing pin, the force acting on these extremities 24' causes the latter to spread outwardly and eventually to be flattened against the wall 17'. The washer 27 thus effectively disables the firing pin, that is to say, the firing pin is prevented from striking the cap 200 of the battery cup. Although the projectile has been made permanently ineffective as an explosive bullet, nevertheless, the more costly and demoralizing danger of having the bullet explode in the gun barrel has been obviated.

What is claimed is:

1. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; and a firing pin in the aperture of said nose, said firing pin being frictionally held normally in said aperture below the end of said nose and adapted on deformation of said heel closure and the resulting forward movement of said core piece in said body to be moved forwardly in said aperture to arm said projectile.

2. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin being frictionally held normally in said aperture below the end of said nose and adapted on deformation of said heel closure and the resulting forward movement of said core piece in said body to be moved forwardly in said aperture to arm said projectile; and means on said pin engageable with the wall of said aperture to positively retain said pin in the nose of said projectile.

3. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin being frictionally held normally in said aperture below the end of said nose and adapted on deformation of said heel closure and the resulting forward movement of said core piece in said body to be moved forwardly in said aperture to arm said projectile; and means between said percussion sensitive element and said firing pin arranged to hold said pin out of contact with said percussion sensitive element in the event egress of said pin from said nose is prevented.

4. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; and a firing pin in the aperture of said nose, said firing pin having a bifurcation at its rear end, the extremities of which are spread apart to engage the wall of said aperture normally to frictionally hold said pin therein below the end of said nose.

5. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; and a firing pin in the aperture of said nose, said firing pin having a bifurcation at its rear end, the extremities of which are spread apart to engage the wall of said aperture normally to frictionally hold said pin therein below the end of said nose, said spread extremities being arranged to be squeezed together on deformation of said heel closure and the resulting forward movement of said core piece in said body to enable said firing pin to move forward in said nose aperture and to arm said projectile.

6. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin being frictionally held normally in said aperture below the end of said nose and adapted on deformation of said heel closure and the resulting forward movement of said core piece in said body to be moved forwardly in said aperture to arm said projectile; and an apertured washer between said percussion sensitive element and said firing pin arranged to hold said pin out of contact with said percussion sensitive element in the event egress of said pin from said nose is prevented.

7. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body;

5 a firing pin in the aperture of said nose, said firing pin being frictionally held normally in said aperture below the end of said nose and adapted on deformation of said heel closure and the resulting forward movement of said core piece in said body to be moved forwardly in said aperture to arm said projectile; and a shoulder on said pin engageable with a shoulder in the wall of said aperture to positively retain said pin in the nose of said projectile.

10 8. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin having a bifurcation at its rear end, the extremities of which are spread apart to engage the wall of said aperture normally to frictionally hold said pin therein below the end of said nose; and an apertured washer between said percussion sensitive element and the spread 15 extremities of said firing pin, said extremities normally being spread apart to span the aperture of said washer whereby the latter is enabled to hold said pin out of contact with said percussion sensitive element and on deformation of said heel closure and the resulting forward movement of said core piece and washer in said body to move said pin forwardly so that its end projects from the nose of said projectile.

20 9. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin having a bifurcation at its rear end, the extremities of which are spread apart to engage the wall of said aperture normally to frictionally hold said pin therein below the end of said nose; and an apertured washer held between said percussion sensitive element and the extremities of said firing pin, said extremities normally being spread apart to span the aperture of said washer whereby the latter is enabled to hold said pin out of contact with said percussion sensitive element and, on deformation of said heel closure and the resulting forward movement of said core piece and washer in said body, to move said pin forwardly whereby the spread 25 apart extremities thereof are squeezed together by engagement with the wall of said firing pin aperture to enable said firing pin to project from the nose of the projectile and to be driven rearwardly on impact with a target through the aperture of said washer into contact with said percussion sensitive material to explode said projectile.

30 10. A projectile comprising a hollow body having a heel end and a nose provided with an aperture; a core piece movable longitudinally in said body and containing a powder charge; a deformable heel closure on said body in engagement with said core; a percussion sensitive element mounted in said core piece adjacent the nose of said body; a firing pin in the aperture of said nose, said firing pin having a bifurcation at its rear end, the extremities of which are spread apart to engage the wall of said aperture normally to frictionally hold said pin therein below

the end of said nose; and an apertured washer held between said percussion sensitive element and the extremities of said firing pin, said extremities being arranged normally to span the aperture of said washer whereby in the event of egress of said pin from said nose is prevented, said washer is enabled on deformation of said heel closure and the resulting forward movement of said core piece in said body to increase the spread of said extremities and hence to permanently prevent contact between said firing pin and said percussion sensitive element.
